UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

REGISTRATION OF PRINTING-PLATES, &c.

1,280,527.

Specification of Letters Patent.

Patented Oct. 1, 1918.

Application filed May 20, 1916, Serial No. 98,917. Renewed February 12, 1918. Serial No. 216,785.

To all whom it may concern:

Be it known that I, EMIL E. NOVOTNY, a citizen of the United States, residing at Riverside, in the county of Cook and State 5 of Illinois, have invented certain new and useful Improvements in Registration of Printing-Plates, &c., of which the following is a specification.

This invention relates to the manufacture 10 of a printing plate from a mold by such a method that the plate may be brought at once into a proper position of exact registration on a printing or supporting base, such as the cylinder of a printing press, in the 15 case of a curved plate, or the flat bed of a press in the case of a flat printing plate, and furthermore such plate when so registered or positioned may be locked by any suitable means, said printing plate preferably during 20 the molding operation having certain indicating means formed thereon which correspond to indicate means on the bed, support or saddle for the plate, so that the plate may be instantly and accurately positioned in any 25 selected location on the surface of the bed by causing the indicating means of the plate to coincide with those on the bed, support or saddle—that is to say, the plate may be interchangeably located on its bed or support. 30 In the printing art, as is well known, an infinite variety of printing must be done on a press. For instance, the margins from the printed matter to the edges of the sheets may differ with different classes of work; 35 the plates, cuts or bodies of type may differ in size and makeup; a particular job may be required to be printed in different superimposed colors; and numerous other factors or conditions well known to printers and 40 pressmen may exist which will necessitate locating the printing element or body, such as the plate, cut or body of type in a particular position upon the supporting part or bed of the press, and this is commonly referred to as registration. Usually the operation 45 of attaining proper register on a press requires so much calculation, in the absence of available means for accurate measurement, that the expenditure of a great deal of 50 time and labor on the part of a skilled pressman, with the consequent expense, is unavoidable.

With my invention I obviate this tedious and costly operation of obtaining accurate 55 registration, as I am enabled to accomplish

this end by my method of preparing the mold and printing plate so that the completed printing plate may be instantly and exactly fitted in the proper position on the support or bed.

Figure 1 is a perspective view showing a portion of a bed or support with the saddle connected therewith, a printing plate registered on the saddle and a sheet of paper located above the printing plate.

Fig. 2 is a plan view of a type form or body of type locked in the chase.

Fig. 3 is a view in elevation showing the formation of a mold from the form of type illustrated in Fig. 2.

Fig. 4 is a plan view of a portion of a casting box intended to illustrate the positioning of the mold in the casting box preparatory to making the plate.

Fig. 5 is a view partly in cross section and 75 partly in elevation showing the making of the plate from the mold in the casting box.

Fig. 6 is a cross sectional view taken through the printing plate and illustrating the uniformly spaced, equi-distant bosses on 80 the back of the plate.

In order to obtain the rapid and exact registration of the printing plate upon its support on the press I provide means for enabling the plate to be instantly applied to 85 such support so that the margin of the printing portion or type matter of the plate will coincide with the marginal line, imaginary or actual on the paper or sheet being fed into printing relation to such plate. For 90 example, if it is desired to print on a sheet so that a blank margin of 1 inch will exist between the printed matter and the edge or edges of the sheet, I provide means by which the plate may be so located on its support 95 in the press, relative to the sheet being operated upon, that this margin will be obtained with exactitude without the necessity of frequent trials to secure proper alignment or registration. Of course where I speak of the 100 paper margin or margins it is to be understood that this is to include various kinds of margins as are encountered in printing, as hereinbefore mentioned, such as those relating to column or cut arrangements, superimposition of colors when necessary, border margins and the like.

As hereinbefore set forth one manner in which my purpose may be accomplished is to 105 provide a plate support of the press, such as

a formed cylinder, or a flat bed, as the case may be, with certain indicating means which are adapted to coincide with certain other indicating means formed on the printing plate, preferably located at the back thereof, occupying a certain predetermined position relative to the printing portion or printing margins at the front face of the plate, that is to say to the top section of the plate.

10 The indicating means on the plate support of the press may be, as shown herein, in the nature of small sockets spaced selected and predetermined distances apart, for example 2 inches. The printing plate may be equipped 15 with small projections or bosses likewise spaced apart distances corresponding to the spaces socketed on the support, that is to say 2 inches. The bosses on the back of the printing plate, however, should be, as herein 20 set forth located relative to the margins or edges of the field of the printing portion at the front of the plate so that when the plate is applied to the support with its bosses seated in the sockets of the support, the 25 margins of the field of the printing portions of the plate will properly coincide with desired paper margins, imaginary or actual, on the sheet to be printed upon.

In practising my invention I preferably 30 proceed as follows, and in order to make my purpose clear I will select a concrete case or example of the application of the invention in connection with a flat printing plate to be used on a press having a flat bed or 35 support.

Let us assume, for example, that we desire 40 to apply to the printing bed 1 in a particular position thereon, a plate 2 having a printing area of 8 by 10 inches shown at 3, and that 45 the sheet of paper 4 to be printed by this plate is 10 by 12 inches, so that the printed sheet will show a margin 5 of one inch at all sides. I take a body of type 6 which is 8 by 10 inches and lock up in the chase 7 there- 50 with two cutting rules 8 at right angles to each other, each spaced one inch from the type matter. When the mold 9 is made from this type body the cutting rules will either score two cutting lines at right angles to 55 each other on the marginal face portions of the mold 9, thus forming indications for cutting or trimming the mold, or will entirely cut or trim off these edges of the mold, so that the type forming matter 10 of the mold 60 will be set in one inch from each of these edges 11. If one edge 11 of the mold is to be changed in the casting box C, as is desirable, an extra width of margin, say, one-quarter of an inch may be left at one side 65 of the mold for this purpose.

When the mold 9 has been thus trimmed it is clamped in the casting box C with the trimmed right angled edges 11 of the mold abutting against the adjacent sides 13 of the 70 casting box. In other words, as the casting

box is usually much larger than the mold, because one casting box is used to make printing plates of different sizes, I snugly fit the mold in one corner of the casting box. This casting box is provided with a core 70 plate 14 which has the face 15 provided with depressions or sockets 16 spaced selected and preferably uniform distances apart, say, two inches from center to center, the centers of the outside rows 16' of sockets also being two 75 inches from the adjacent edges of the core plate and also the inner faces of the adjacent sides of the casting box side walls.

Upon the mold 9 is placed a sheet of plastic plate making material 17 and the plate 80 is formed by closing the top 18 of the casting box and depressing the core plate against the plastic material and also the mold. The result is that bosses or projections 19 are formed on the back 20 of the 85 printing plate. Considering the back 20 of the plate, these bosses 19 will be spaced two inches apart relative to each other, with the marginal rows of bosses also two inches from the edges of the plate, but considering the 90 front or printing face 21 of the plate, these marginal rows of bosses will lie inward one inch from the marginal printing lines. Furthermore, the sockets 16 of the core plate of the casting box and consequently the bosses 95 19 made on the back of the printing plate are made to correspond or standardized with sockets 22 formed in the bed or saddle 1 of the press, that is the bed or saddle 1 has formed in its outer face sockets spaced two 100 inches apart to receive the bosses of the printing plate.

Now, it will be evident that the marginal trimming lines or edges on the mold are also the marginal printing lines on the paper, or 105 represent the edges of the paper, and that therefore the finer dimension rather than the rough possible shiftable dimension provided for by the bosses on the plate and the sockets in the bed or saddle on a printing press is 110 further minutely dimensioned by the shifting of the relative positions of the bosses of the plate and the printing margins on the front or face of the plate.

In the casting of the printing plate, core 115 screws 23 are preferably projected through the sockets in the core plate to form screw bores 24 in the bosses of the plate, so that suitable fastening screws, preferably hollow, may be used to secure the plate bosses in the 120 sockets of the saddle.

It will be noted that my invention embraces this. Given a printing plate having the back thereof provided with indications or markings such as the bosses constitute, 125 which correspond in spacing and relative location to indications or markings on the plate support or bed on the press, such as the sockets constitute, the plate may be instantly and accurately registered on the bed 130

or saddle or support on the press, irrespective of the distance the marginal edges of the printing or type portion of the plate may be from the edges of such plate.

- 5 It will further be noted that in the present exemplification of the invention I have shown and described the bosses of the plate and the sockets of the bed or saddle as constituting the corresponding or related indicating or locating means for obtaining the proper register of the plate on the bed or saddle, but it will be understood that I do not limit myself to this nor to the formation of the indicating means on the plate during 10 the molding operation, as other indicating means, such as surface lines or points or depressions might be used on the plate and its supporting saddle or bed, and these might be applied to the plate after as well as before it is made. Furthermore, the invention is applicable to plates or printing bodies made otherwise than by molding. The example and explanation given herein is merely by way of illustration.

25 What I claim is:

1. The herein described method of registration which comprises providing a printing plate with a registration indication occupying a predetermined position relative 30 to a marginal printing line of such plate and applying a plate to a plate support on the press with such indication so positioned relative to the indication of the plate support of the press that the marginal printing 35 line of the printing plate will coincide with a selected line of the paper printed upon.
2. The herein described method of registration which comprises providing a non-printing portion of a printing plate with 40 a plurality of spaced registration indications, certain of which indications occupy a predetermined position relative to a marginal printing line of the plate, and applying a plate to a plate support on the press 45 with such indications so positioned relative to an indication on the plate support of the press that a marginal printing line of the printing plate will coincide with a selected printing line of the paper printed upon.
- 50 3. The herein described method which comprises providing a printing plate support with spaced registration indications and providing the printing plate with similarly spaced registration indications adapt- 55 ed to correspond with those of the support, certain of the registration indications of the printing plate being spaced a predetermined or measured distance from the printing margin of the plate to cause such printing margin to coincide with a line margin 60

of the paper when the plate is applied to the support.

4. The herein described method of registration or positioning printing body on a support which comprises providing non-printing portions of the body with indicating means adapted to correspond and selectively register with a plurality of spaced indicating means on this support. 65

5. The herein described method of registration or positioning a printing body on a support which comprises providing a body with a plurality of spaced indicating means adapted to correspond and selectively register with a plurality of similarly spaced 70 indicating means on a support whereby said printing body may be accurately registered on the support in any desired location. 75

6. The herein described method of registering or positioning a printing body on its support which comprises providing a back face of a printing body with a plurality of spaced indicating means adapted to correspond to and selectively register with a plurality of similarly spaced indicating 80 means on the printing or adjacent face of the support. 85

7. The herein described method of registering or positioning a printing plate on its support which comprises providing a back face of a plate with a plurality of uniformly spaced projections adapted to correspond to and selectively coincide with a plurality of similarly spaced sockets or recesses in the support. 90 95

8. The herein described method of preparing for registration and registering a printing plate on its support which consists in molding a plate and forming indicating means on the back thereof by means of a device having spaced indications corresponding or standardized to spaced indications on the support and subsequently fitting the plate on the support to cause 100 the indications of the plate to coincide with the indications of the support. 105

9. The herein described method of registering or positioning a printing body on its support which comprises providing a body with a plurality of spaced indicating means adapted to correspond and selectively register with a plurality of similarly spaced indicating means on a support whereby said printing body may be accurately registered on the support in any desired location, and 110 providing holding means at points where the indicating means of the body register with the indicating means of the support. 115

In testimony whereof I affix my signature.
EMIL E. NOVOTNY.
